(57) CLAIM

The ornamental design for a rocker body as shown and described.

DESCRIPTION

FIG. 1 is a top perspective view of a rocker body; FIG. 2 is a bottom perspective view thereof; FIG. 3 is a front elevational view of thereof; FIG. 4 is a rear elevational view thereof; FIG. 5 is a top plan view thereof; FIG. 6 is a bottom plan view thereof; and, FIG. 7 is a left side elevational view thereof, a right side elevational view is not shown because it is a mirror image of the left side elevational view.
The broken lines shown in the drawings form no part of the claimed design.
